BOOK SUPPORT WITH INDEPENDENT COVER HOLDER

William Gramacy, Bronx, N. Y.

Application April 30, 1957, Serial No. 656,145

2 Claims. (Cl. 45—61)

This invention relates to a book support for supporting and holding a book with the pages of the book in open spaced-apart flatwise condition.

A principal object of the present invention is to provide a book support that is especially designed for use in holding a book in open condition when reading in bed, without the necessity of use of the hands by the reader.

Another object of the invention is to provide a book support that holds the page of the book in open position, but permits ready turning of a page, when so desired.

A further object of the invention is to provide a book support that is portable, easily manipulated, and that is readily supported in a horizontal or upright inclined extended position.

It is also proposed to provide a book support that is simple and sturdy in construction and that can be manufactured and sold at a reasonable cost.

For further comprehension of the invention and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a top plan view of a book support embodying my invention, the book support being shown lying flat in collapsed condition on its supporting surface and supporting a book, a page of the book being shown partly turned;

Fig. 2 is an edge view thereof looking toward the top portion of Fig. 1;

Fig. 3 is a side elevational view of the book support with a book thereon, the support being here shown in extended position, for mounting on a desk or other support;

Fig. 4 is a fragmentary side elevational view similar to Fig. 3 but with the book removed, and showing a clamp-finger in open or inoperative position;

Fig. 5 is a sectional view taken on the plane of the line 5—5 of Fig. 1; and

Fig. 6 is an enlarged sectional view taken on the plane of the line 6—6 of Fig. 5.

Referring in detail to the drawing, in Fig. 1 a book support embodying the invention is designated generally at 10. This book support comprises a rectangular-shaped plate 11 constituting the body of the support. The plate may be made of stiff cardboard or similar material having a smooth surface. A narrow metal plate 12 extends along one longitudinal side edge of the body, and is fastened thereto by rivets 13.

A pair of spaced metal clamping units, each indicated generally at 14, are disposed perpendicularly to the plate 12 and rigidly secured thereto. Each clamping unit comprises a wide metal finger 15 secured at one end to the inner edge of the plate 12 by rivets 16 or other suitable means and provided with an upturned bent end 17. A hinge device indicated generally at 18 is disposed outwardly of the fastened end of the finger 15, in line there-

2

with and closely spaced therefrom. This hinge device consists of two hinged leaves 19 and 20 formed of spring metal and a pin 21 connecting the leaves. The leaves are narrower in dimension than the finger 15. Leaf 19 is secured at one end to the plate 12 by rivets 22, and is formed at its other end with outstruck spaced curled knuckles 23 sleeved around the hinge pin 21. Between the knuckles 23, the leaf is formed with an outstruck lug 24 extending at right angles to the plane of the body of the leaf and being formed with a smooth curved end edge. The lug extends slightly outwardly of the outermost portion of the knuckles 23.

Hinge leaf 20 has one end formed with outstruck curled knuckles 26 sleeved around the pin 21. The body 15 of the leaf is slotted to form an elongated lug 27 bent slightly outwardly of the plane of the body of the leaf and having its outer free end engaging and slidably over the curved outer end edge of the lug 24 of leaf 19. This construction and arrangement of leaves and lugs cause the lugs 27 to urge the leaves 20 into closed relation with the leaves 19.

An angular substantially inverted V-shaped finger 28 of spring metal, narrower than the finger 15, is secured to the unhinged end of the leaf 20 by means of rivets 29, or other suitable means, extending through the leaf end and through a flange or extension 30 formed on the end of the short side 31 of the finger 28. The inner surfaces of the longitudinal sides 32 of the fingers are smooth and the free ends thereof are slightly bent outwardly.

30 A plate 33 constituting a brace is secured to the end of the plate 11, opposite the end mounting the plate 12, preferably by means of a piano hinge 34. One leaf 35 of the hinge is fastened to the plate 11 by rivets 36 or the like, and the other leaf 37 is fastened to the adjacent end of the plate 33 by rivets 38 or the like. A small plate 39 is fastened to the plate 33 at the center of its hinged end, as by rivets. This plate 39 extends beyond the end edge of the bracing plate 33 and over the knuckles 40 of the piano hinge, the extending edge of the plate 39 engaging the leaf 35 and thereby limiting outward extensive movement of plate 33, and holding the plates 11 and 33 in open extended condition as shown in Fig. 3.

In use, the book support may be placed flatwise in collapsed condition on the lap of the reader, or the bracing plate 33 may be opened and extended and the book support placed on the top of a desk or table. When in this latter extended position, the rest plate 11 is disposed in an upstanding manner and inclines rearwardly from its bottom to its top so as to support the book in an upstanding rearwardly inclined position, so that the book may be conveniently read.

55 In order to mount the book on the book support, the clamping fingers 28, 28 are swung outwardly to open position as shown in Fig. 4 and a book 41 opened flatwise at the desired place is placed on the rest plate 11. The open book covers are slid under the fingers 15, 15 until the leading end edges of the covers abut against and seat upon the top edge of plate 12, with the heel portion 42 disposed between said fingers as shown in Fig. 2. The clamping fingers 28, 28 are then swung to closed clamping position over the leaves 43 of the book. When the book is in this supported position, the outwardly turned end edges 17, 17 of the fingers 15, 15 tend to press outwardly against the leaves and the spring loaded fingers 28, 28 due to their shape and to the spring lugs 27, 27 tend to press inwardly against the leaves so that the book is securely held in position. The outwardly curved end edges of the long sides 32 of the fingers 28, 28 and the spring action of said fingers permit ready turning of a page by simply pushing upwardly and laterally by the finger of the user against the page desired to be turned whereby it readily moves upwardly

and laterally as shown in Fig. 1, such movement being facilitated by the smooth inner surfaces of the long sides 32, 32 of the fingers.

Furthermore, one or both of the fingers 28 may be swung away from the leaves any desired distance and due to the frictional engagement of the spring lugs 27 on the outrucked lugs 24, said finger or fingers will be held in such moved position, permitting ready turning over of a page. The swinging of the finger or fingers and the turning over of the page or pages may be done with one hand so that the construction is beneficial to a person in bed or to an invalid.

While I have illustrated and described the preferred embodiment of my invention, it is to be understood that I do not limit myself to the precise construction herein disclosed and the right is reserved to all changes and modifications coming within the scope of the invention as defined in the hereunto appended claims.

I claim:

1. A book support comprising a rectangular-shaped, flat, solid, plate constituting a book rest, a narrow plate fixed on the front surface of the rest plate, along the bottom edge thereof, a pair of clamping units spaced along and disposed perpendicularly to the bottom long edge of the rest plate, on the front surface thereof, each unit consisting of an elongated flat finger fixed at one end to the narrow bottom plate and extending inwardly thereof of closely spaced from the rest plate to receive the covers of an open supported book thereunder, a second finger hingedly secured at one end to the outer end of the elongated flat finger, said second finger being substantially inverted V-shaped with the free end thereof spring-pressed inwardly toward the other elongated flat finger and being adapted to press upon the leaves of an open supported book, and a bracing plate hingedly mounted on the rear surface of the rest plate along the opposite longitudinal edge thereof for supporting the book support in an inclined position, said bottom narrow plate having a straight upper edge serving as an abutment for the bottom edges of the covers of an open supported book to limit inward movement of the book.

2. A book support comprising a flat, solid, rectangular shaped plate constituting a book rest, said plate having parallel top and bottom longitudinal edges, a pair of clamping units secured along and disposed perpendicularly to the bottom longitudinal edge on the front surface of the rest plate, each unit consisting of a pair of aligned fingers of varying lengths and widths, the narrow and shorter finger of each pair being substantially inverted V-shaped, the wide finger of each pair being elongated and flat and fixed at one end to the rest plate, said elongated wide fingers being closely spaced from the rest plate to receive thereunder the covers of an open supported book, the narrow finger of each pair being hingedly connected at one end to the fixed end of the respective wide finger, the hinge connection including a hinge leaf secured at one end to the fixed end of the wide finger, the other end of the hinge leaf having spaced knuckles and an outstanding lug therebetween, a hinge leaf secured at one end thereof to one end of the companion narrow finger, the other end of the latter hinge leaf having spaced knuckles aligned with the knuckles on the first-named hinge leaf, a hinge pin extending through the knuckles of each pair of leaves, said last-named hinge leaf having an elongated spring lug offset from the plane of the hinge leaf and frictionally pressing against and slidably over the free end of the lug of the first-named hinge leaf for urging the narrow finger toward the associated wider finger, said elongated spring lugs being adapted to frictional engagement with said free ends of the lugs to hold the narrow fingers in either wholly open position or partly open position, whereby the hand of the user is free to manipulate the book or leaves thereof.
